UNITED STATES PATENT OFFICE

WALDO F. PEREZ, OF JACKSONVILLE, FLORIDA

GASOLINE-DISPENSING PUMP

Application filed August 16, 1928. Serial No. 300,064.

The present invention is directed to improvements in gasoline dispensing pumps.

The primary object of the invention is to provide a device of this character so constructed that gasoline can be dispensed without the service of an attendant.

Another object of the invention is to provide a device of this character so constructed that upon the insertion of a coin of the proper 10 denomination a lever will be interlocked with the valve mechanism to simultaneously discharge gasoline from one bowl, while another bowl is being refilled.

Another object of the invention is to provide a device of this character constructed and arranged in such manner that the operating lever will be maintained in an inoperative condition to prevent operation of the valve mechanism until a coin of the proper 15 denomination has been deposited in the apparatus.

With these and other objects in view, this invention resides in the novel features of construction, formation, combination and arrangement of parts to be hereinafter more 20 fully described, claimed and illustrated in the accompanying drawings, in which:—

Figure 1 is a side elevation of the pump.

Figure 2 is a side view, partly in section.

Figure 3 is a sectional view on line 3—3 of 25 Figure 4.

Figure 4 is a side view, partly in section, of the valve mechanism and coin controlled apparatus.

Figure 5 is a face view of the valve pit.

Referring to the drawings, 1 designates a 30 conventional form of pump stand in which is extended the gasoline supply pipe 2 leading from the storage tank, not shown, the gasoline being forced through said pipe by compressed air, as usual.

Mounted in the stand is a casing 3 formed from complementary circular sections 4 and 5, the confronting faces thereof being provided with packing rings 6—6 and 7 for effectively packing the valve disk 8 rotatable in said casing. The valve disk is fixed to the shaft 9 which is rotatable in the packed bearings 10—10 of the sections, one end of said shaft having a pinion 11 fixed thereto, the purpose of which will appear later.

The valve disk 9 is provided with a pair of diametrically disposed passages 12 and 13.

Supported upon the stand are gasoline containing bowls 14 and 15, and leading from the bowl 14 are pipes 16 and 17, the pipe 16 connecting with the casing at the point A and has its lower end alined with the upper end of the pipe 18 disposed upon the opposite side of the casing and having communication with the upper end of the inlet pipe 2, the pipe 18 being connected also with the inlet pipe 2.

The pipe 17 has its lower end connected to the casing at the point B and in alinement with the upper end of the pipe 19 upon the opposite side of the casing, the latter pipe connecting with the discharge pipe 20.

Leading from the bottom of the bowl 15 are pipes 21 and 22, the former being connected at its lower end to the casing at the point C and in alinement with the upper end of the pipe 23 disposed upon the opposite side of the casing, said pipe 23 being connected to the inlet pipe 2.

The pipe 22 is connected to the casing at the point D and is alined with the pipe 24 upon the opposite side of the casing, said pipe being connected with the discharge pipe 20.

A coin receiving drum 25 is employed and has fixed centrally thereof a shaft 26 journaled in the sides 27—27 of the coin chute 28. This drum is provided with coin receiving pockets 29, four in number, said pockets having inclined bottom walls 30 in order that the coins will roll fully within the pockets and stop against the end walls 31 thereof.

These pockets are capable of being successively brought into registration with the coin entrance chute 32 carried by the wall of the pump stand.

A lever 33 is provided for rotating the drum and has its lower end provided with an abutment 34 which has formed integral therewith spaced arms 35 adapted to span the drum, said arms having their lower ends provided with bearings 36 for loosely engaging the shaft 26 in order that the lever can be swung freely.

The chute 28 has a bracket 37 carried thereby and connecting the bracket and lever is a coil spring 38, which normally holds the le-

ver in its inoperative position in the slot 39 formed in the stand, there being a rubber bumper 40 in the upper end of the slot to absorb the shock incident to the rebound of the lever when released.

5 Fixed to the shaft 26 is a gear 41 which meshes with the pinion 11, the gear ratio being such that when the gear is rotated one-quarter revolution the disk valve 8 will make 10 one-quarter revolution.

When a coin of the proper denomination is deposited in the chute 32 it will roll therefrom into the pocket in registration therewith, a portion of the coin projecting from 15 the slot in order that the abutment 34 will engage the projected part of the coin to interlock the lever and drum so that when the lever is rocked the drum and valve will be compelled to make one-quarter revolution after 20 which the lever is released and returns to its inoperative position under the influence of the spring 38.

It will, of course, be understood that the 25 pockets will be brought selectively into registration with the chute 32.

Assuming that the disk valve 8 is in the position as shown in Figure 4 and the passages 12 and 13 are in registration with the opposed ends of the pipes 17 and 19 and pipes 21 and 30 23, respectively, gasoline under pressure in the pipe 2 will flow into the pipe 23, through the passage 13 into the pipe 21 and into the bowl 15 to fill the same. At the same time fuel from the bowl 14 passes through the pipe 35 17, through the passage 12, pipe 19 and into the discharge pipe 20 to the tank filling hose 42.

When the disk valve is again rotated one-quarter revolution the passage 12 registers 40 with the opposed ends of the pipes 16 and 18 while the passage 13 registers with the opposed ends of the pipes 23 and 24, thus permitting gasoline from the pipe 2 to flow through the pipes 18 and 16 to refill the bowl 45 14, while the contents of the bowl 15 is being discharged through the pipe 22, passage 13, and pipe 24 to the filling hose.

It will be seen that when one bowl is being 50 emptied, the other is being refilled.

55 The drum has carried thereby four cams 43 adapted to successively engage a contact member 44 of any approved construction for starting the usual pressure pump for forcing gasoline to the empty bowl.

From the foregoing, it is thought that the construction, operation and many advantages of the herein described invention will be apparent to those skilled in the art, without further description, and it will be understood that various changes in the size, shape and proportion and minor details of construction, may be resorted to without departing from the spirit or sacrificing any of the advantages of the invention.

What is claimed is:—

1. A coin controlled mechanism comprising a chute, a shaft journaled in the chute, a drum fixed to the shaft and having radial coin receiving pockets formed therein, an actuating lever having an abutment, spaced arms depending from the abutment for spanning the drum, said arms being pivotally connected to the shaft, and means for depositing a coin into a pocket of the drum for engagement with the abutment of the lever.

2. A coin controlled mechanism comprising a chute including sides, a shaft journaled in said sides, a drum fixed to the shaft, radially disposed coin receiving pockets formed in the drum and including inclined bottom walls, said pockets having one of their ends closed by end walls for limiting the movement of coins therein, a bracket carried by the chute, an actuating lever having an abutment, arms depending from the abutment and spanning the drum, said arms having their lower ends pivotally engaged with the shaft, a spring connecting the lever and bracket, said abutment being adapted to engage a coin deposited in a pocket to rotate the drum upon swinging the lever in one direction, said spring serving to swing the lever in a reverse direction when released.

In testimony whereof I affix my signature. 95
